UNITED STATES PATENT OFFICE.

HERMAN W. EICHBAUM, OF VENICE, CALIFORNIA.

DESIGN FOR A VEHICLE-BODY.

50,125.

Specification for Design.

Patented Jan. 2, 1917.

Application filed June 20, 1916. Serial No. 104,827. Term of patent 7 years.

To all whom it may concern:

Be it known that I, HERMAN W. EICHBAUM, a citizen of the United States, residing at Venice, in the county of Los Angeles and State of California, have invented a new, original, and ornamental Design for Vehicle-Bodies, of which the following is a specification, reference being had to the accompanying drawing, forming part hereof.

In the drawing, Figure 1 is a plan view,

and Fig. 2 is a side view, of a vehicle body, each one showing my new design.

I claim:

The ornamental design for a vehicle body, as shown.

HERMAN W. EICHBAUM.

Witnesses:

ALFRED H. DAEHLER,
LOUIS S. ARNOLD.
